UNITED STATES PATENT OFFICE.

HARRY F. KEIFFER, OF PERRYSBURG, OHIO.

AUXILIARY VALVE FOR INTERNAL-COMBUSTION ENGINES.

1,168,309.

Specification of Letters Patent. Patented Jan. 18, 1916.

Application filed October 19, 1914. Serial No. 867,382.

To all whom it may concern:

Be it known that I, HARRY F. KEIFFER, a citizen of the United States, and a resident of Perrysburg, in the county of Wood and State of Ohio, have invented a certain new and useful Auxiliary Valve for Internal-Combustion Engines; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

My invention relates to valves for supplying air to internal combustion engines in addition to that which is supplied through the carbureter.

The operation of the valve is automatic in its character in that the amount of air which is furnished to the engine when running at full speed, is reduced when the engine is operating at a lower speed.

In the embodiment of my invention, a spring controlled valve member is operated by the difference in the pressures of the atmosphere on one side of the valve member and that of the mixture of vapor and air produced by the carbureter on the other.

By the use of my invention, the consumption of the fuel, such as, the gasolene, is greatly reduced, for, as the engine becomes heated and the speed of the engine increases, a better mixture of air and gasolene will be made for operating the engine under high speed. Also, in my invention, a means is provided for using the warm air which is heated by some part of the engine. The air is preferably taken from in the vicinity of the exhaust pipe. A means is provided which will draw the air from some part of the engine and yet which may be turned away so as to draw the air from a point remote from the engine. The warm air assists in the vaporization of the gasolene particularly in cool weather. On the other hand, in warm weather the device may be altered so as to draw the air from a point remote from the engine to prevent overheating of the engine.

The invention may be contained in many constructions, all of which come within the purview of my claims hereinafter appended. To show the practicability of constructions embodying my invention, I have selected one

of such constructions as an example and shall describe it hereinafter. The construction selected is illustrated in the accompanying drawing.

Figure 1 of the drawings illustrates an embodiment of my invention as applied to the intake pipe of an engine. Fig. 2 illustrates a longitudinal sectional view of the device shown in Fig. 1. Fig. 3 illustrates a top view of the valve containing part.

1, Fig. 1, illustrates the engine to which the device is applied. 2 is the intake pipe leading from the carbureter 3 to the engine 1. In multi-cylinder engines, the intake pipe 2 forms the manifold of the engine. The device 4 is secured to the engine. It is preferably secured to the intake pipe 2. 5 is the exhaust from the vicinity of which the air, which is drawn through the device 4, 75 may be taken.

The device 4 is provided with a flanged connector 10 having openings through which screws 11 may be inserted to secure the device to the intake pipe 2. The flange connector 10 is provided with a hole 12 in which the body 13 of the device may be threaded which secures the device 4 to the pipe 2. The casing 13 is provided with an opening 14 which registers with an opening in the 85 intake pipe 2. The passageway 14 is controlled by a cock 15 which may be turned to reduce or close the passageway through the body of the casing. A screw 16 may be used for holding the cock 15 in position. The 90 body of the device 4 may be located horizontally while the cock 15 which is located at right angles to the axis of the device 4 may extend vertically. The cock 15 may be provided with a passageway 20 and a cup 21 95 which communicate with the interior of the intake pipe 2 through the passageway 14. If it is desired, the cup may be used for priming the engine. The passageway 20 is controlled by a second cock 22 having a 100 handle 23 which is secured in position by the threaded pin 24 and nut 25. The handle 23 is not only useful in closing the cock 22, but it also is used in operating the cock 15.

The casing 13, at its outer end, is recessed by a counter bore. The recess is threaded and receives a valve casing 52 which has a portion forming a cylinder extending into the body 13. The valve casing 52 is also 110 recessed and contains the puppet valve 27 having a cone end which seats upon the edge

of a counter bore 26 in the casing 25. The cone end permits an extended horizontal movement of the movable valve member and yet guides the valve member to its seat, notwithstanding such extended movement. The movable valve member is provided with a stem 29 which freely moves in a cross bar 30. The cross bar 30 is threaded into the recess 31 in which the movable valve member 27 is located. A spring 32 is located intermediate the valve member 26 and the cross bar 30. The threaded cross bar forms a convenient means for guiding stem 29 and also forms an adjustable means for regulating the tension of the spring 32. Moreover the combination permits ready assemblage and separation of the parts for the purpose of cleaning as well as for easy and convenient adjustment of the movable valve member.

The valve casing 25 may be locked to the body 13 by any suitable means to prevent rotation of the casing 25 relative to the body 13 which might be caused by the jarring of the engine while in operation. I have shown a screw 35 which may be threaded into the abutting shoulders of the two casings so as to prevent rotation of one relative to the other. The movable valve member 26 may also be provided with a guiding plate 33 having right angularly turned fingers 34 located in the vicinity of the interior surface of the wall of the recess 31 which also aids in keeping the valve member centrally located.

The end of the casing 25 is provided with an inlet 39. It is preferably connected to a tube 40 which is threaded into the casing 25 and communicates with the counter bore 26. The tube 40 is preferably angular having the angular portion 41 so positioned that it may be brought into contact with, or into the vicinity of some heated part of the engine when it is desired to draw heated air into the engine to cause it to mix with the mixture arising from the carburetor. A plurality of threaded semi-circular holes 45 may be formed in one of the abutting shoulders of the casing such as the shoulder 46 to form a plurality of locking points. They provide vertical and circular adjustments of the location of the tube 40 and the parts may be locked in any one of the positions by means of the screw 35. The tube 40 may be turned in the casing 25 so as to provide a transverse adjustment of the outer end of the tube 40. By this means the tube 40 may be adjustably located in such a position that its end will be in proximity to some heated portion of the engine. When the engine is operated under conditions, such as in the summer time or under condition which will be apt to cause overheating of the engine, the tube 40 may be turned in the casing 25 so as to draw air from a point which is away

from the engine and which is not heated by it.

When it is desired to prime the engine by using the priming cup 21, the cock 22 is opened and when suction is produced by the down stroke of the piston of the engine, the priming gasoline will be vaporized by the air which passes in through the tube 40 and through the valve 26 into the passageway 14. The passageways 20 and 14, being at right angles to each other, aid in the dissemination of the gasoline drops. Furthermore, the priming of the engine may be further assisted by heating the tube 40. The priming gasoline may then be inserted in the cup 21 and the air which passes through the tube 40 will be warmed by the increased temperature of the tube which will assist in the starting of the automobile engine.

The construction selected and described may be greatly varied in the arrangement and connections of its parts and in the substitution of elements having equivalent functions, and, such modifications, may be used for widely different purposes and may still contain the invention.

Having thus described my invention, what I claim as new and desire to secure by Letters Patent, is,

1. The combination of a valve casing, a threaded cylinder located within the casing, a cross bar having threads extending across the ends and threaded in the cylinder, a cone valve member having radially extending fingers and seated on the end of the cylinder, a stem secured to the movable valve member and freely movable through the cross bar, a spring located on the rod and intermediate the valve member and the bar, and means for adjustably varying the pressure of the spring.

2. The combination of a manifold and a carburetor, an auxiliary valve connected to the manifold and comprising a valve casing having a stop cock at one end and a valve casing having a movable bent intake tube for taking air more or less remote from heated pads of the engine at the other end, a cross bar located in the valve casing and having its ends threaded to engage with the threaded walls of the cylinder, a movable valve member having radially extending fingers, the outer ends of which are bent at right angles and longitudinally to the casing, the movable valve member seated on the end of the cylinder communicating with the tube, a rod connected to the movable valve member and movable in the cross bar, a spring located intermediate the cross bar and the valve member.

3. In combination with a carburetor of an internal combustion engine, a valve casing having a passageway extending therethrough, a valve member for controlling the passageway, a stop cock located interme-

diate the valve member and the engine also for controlling the passageway, the cock having a priming cup and a passageway communicating with the passageway of the 5 casing and a stop cock located in the first-named stop cock for controlling the second passageway.

4. In combination with the carbureter of an internal combustion engine, a casing having a passageway communicating with the engine, a stop cock for controlling the passageway, the stop cock having a cup and a passageway connecting the cup with the first-named passageway, a stop cock for controlling the second passageway in the first-named cock.

5. In combination with the carbureter, a valve casing having a passageway therethrough and communicating with the engine, an adjustable tube communicating with the passageway of the casing, a valve member having a cone for guiding the valve member to its seat, a stem secured to the valve member, a cross bar having threaded 25 ends and an opening through which the stem is movable, a spring located intermediate the cross bar and the movable valve member, a cock also for controlling the passageway and having a priming cup and a 30 controlling cock.

6. In combination with the carbureter of an internal combustion engine, a casing having a passageway communicating with the engine, a spring-pressed valve member for controlling the passageway and a movable 35 bent tube communicating with the passageway for receiving air in the vicinity of or remote from a heated portion of the internal combustion engine.

7. In combination with the carbureter of an internal combustion engine, a casing having a passageway communicating with the engine, a spring-pressed valve member for controlling the passageway, a casing for containing the said spring valve member and 45 threaded into the first-named casing; means for locking the second-named casing at different points about the axes of the two casings and a movable bent tube secured in the second-named casing and communicating 50 with the passageway for receiving air in the vicinity of or remote from heated portions of the internal combustion engine.

In testimony whereof, I have hereunto signed my name to this specification in the 55 presence of two subscribing witnesses.

HARRY F. KEIFFER.
